[57] **CLAIM**

The ornamental design for a toy armoire, as shown and described.

DESCRIPTION

FIG. 1 is a front perspective view of a toy armoire in accordance with our new design;

FIG. 2 is a front elevational view thereof;

FIG. 3 is a back elevational view thereof;

FIG. 4 is a side elevational view thereof, the opposite side being a mirror image;

FIG. 5 is a top plan view thereof;

FIG. 6 is a bottom plan view thereof; and,

FIG. 7 is a perspective view thereof in the same position as in FIG. 1, but with one door slightly ajar.
